IMMISCIBLE LIQUID COUNTERCURRENT
METHOD AND APPARATUS

Matthew D. Mann, Jr., Roselle, N. J., assignor to
Standard Oil Development Company, a cor-
poration of Delaware

Application February 26, 1932, Serial No. 595,330

9 Claims. (Cl. 23—276)

This invention relates to counter-current treatment of fluids. The invention will be fully understood from the following description taken in connection with the accompanying drawing, in which latter

Fig. 1 is a longitudinal sectional view of one form of apparatus suitable for carrying out the invention;

Fig. 2 is a longitudinal sectional view of a modified form of apparatus; and

Fig. 3 is an enlarged perspective view of another form of pipe.

The invention is directed particularly to the counter-current treatment of immiscible liquids of different gravities and will be described for illustration first in connection with the counter-current treatment of soap solution, containing dissolved paraffin wax, with naphtha. Such mixtures are obtained in the manufacture of soaps from oxidized paraffin wax, and require purification by removal of wax which has not reacted.

Referring particularly to Fig. 1 of the drawing, there is shown a tower, the shell of which is designated by reference numeral 1. The shell is divided vertically into sections by means of a plurality of plates 2 which extend horizontally across the tower. One or more pipes 3, communicating with openings in the plates 2, extend upwardly from each plate for a substantial distance sufficient to permit the accumulation of a layer of the heavy liquid, such as soap solution containing paraffin. The pipes 3 are provided with openings for sub-dividing the heavy liquid into drops. In the embodiment illustrated in Fig. 1, the ends 3' of the pipes projecting above the plates 2 are serrated or jagged to form the openings to subdivide the heavy liquid into drops as it enters the pipes from the accumulated layer.

Other means of subdividing the liquid may be used such as pipes having small openings or holes in the sides, through which openings the liquid upon passing is divided into drops. Such a form is denoted by 3a in Fig. 3. Baffles 4 in the form of chimneys or plates may also be arranged below each opening of the pipes 3, to deflect the direct flow of the heavier liquid from the pipes in one plate to the accumulating layer of the next plate and also help the contact of the two immiscible liquids.

The relatively light liquid such as naphtha is passed into the lowermost section through a line 5 at a rate of flow controlled by any suitable means, not shown. The relatively light liquid flows upwardly through the shell from one sec-

tion to another through pipes 3, and is discharged from the uppermost section through a discharge line 6. The relatively heavy liquid, such as soap solution containing paraffin, is introduced into the uppermost section through a line 7 at a rate of flow controlled by any suitable means, not shown. The relatively heavy liquid flows downwardly from one section to another through pipes 3 and is discharged from the lowermost section through a line 8. The feed of relatively heavy and relatively light liquids into the shell can be a proportional rate of flow controlled as desired.

In the operation of this process the tower is first filled with the relatively light liquid and the two immiscible liquids are then passed into the tower. The downwardly flowing relatively heavy liquid is fed into the tower at a rate proportional to the discharge through drains 6 and 8, to cause accumulation of the heavy liquid above each plate in layers of substantial thickness. The depth of the heavy liquid layer above each plate is controlled by the distance pipes 3 projecting above the plates 2. The heavy liquid gathered in a layer on the plates 2, upon rising to a level with the top of the pipes and upon flowing into pipe 3 is subdivided into drops by means of the serrated or jagged ends 3'. The size of the drops is governed by the depth of serration in the ends of the pipe 3. Where pipes having holes in the sides are used, the size of the holes governs. The drops pass downwardly through the pipes 3 in contact with the relatively light liquid passing upwardly through the said pipes. The relatively heavy liquid passing downwardly from the pipes 3 is diverted from direct flow to the pipes 3 of the plate beneath by baffles 4 and flowing over the edges of the baffles flows to the accumulating area. In place of the baffles a similar effect may be produced by so arranging the pipes 3 of each plate so that they are not directly in line with the pipes of the plates beneath and above.

Numerous subdivisions of the relatively heavy liquid flowing downwardly are thus made and better contact with the light liquid is accomplished before the two liquids are withdrawn at their respective drains.

Fig. 2 illustrates a modified counter-current scrubber where it is desirable to wash a lighter liquid with water. For illustration, the lighter liquid is a fatty acid containing sulphuric acid and the heavier wash liquid is water. In this modified scrubber the shell is designated by numeral 9. The shell is divided vertically into

sections by means of a plurality of plates 10 which extend horizontally across the tower. One or more pipes 11 communicating with openings in the plates 10 extend downwardly from each plate for a substantial distance, sufficient to permit the accumulation of a layer of the lighter liquid passing upwardly through the tower. The ends 12 of the pipes projecting below the plates are serrated or jagged in form to subdivide the lighter liquid into drops as it passes into the pipes from the accumulated layer. Baffles 13 in the form of plates may also be arranged above each opening of the pipes 11 to deflect the flow of the lighter liquid from the pipes in one plate 15 to the accumulating layer of the next plate above. In place of baffles, an arrangement of the pipes of each plate, so that they are not directly in line with the pipes of the plates above and beneath, will produce the same effect.

20 There is provided an inlet 14 for passing into the tower the heavier wash liquid and an outlet 15 for removing the heavier wash liquid with the impurities. Inlet 16 is used to pass the lighter liquid that is to be purified into the tower 25 and outlet 17 is used to remove the purified lighter liquid from the tower.

In the operation of this counter-current scrubber the tower is filled with the heavier liquid, water in this case. The lighter liquid such as 30 fatty acid containing sulphuric acid as an impurity is passed into the tower through pipe 16 and more water is also introduced through pipe 14. The rate of flow of the two liquids may be adjusted as desired and is governed by the purity 35 of the fatty acids being removed through pipe 17. The fatty acid upon passing through the tower accumulates in layers beneath each plate and is subdivided into drops by means of the serrated end 12 of pipes 11 as it enters the pipes. The 40 drops flowing upwardly through the pipes 11 are brought into intimate contact with water flowing from opening 14 to drain 15. The purified fatty acid is withdrawn through drain 17 and the water with the sulphuric acid in solution is withdrawn 45 through drain 15.

The examples given are for illustration only, as this apparatus may be used in any counter-current purifying process, being limited only to 50 two or more liquids which are immiscible with each other and have enough difference in specific gravity to form layer separations.

Other examples are:

Washing oil soluble sulphonate acids from treated oil with dilute alcohol. In this case the alcohol may have impurities which will be dissolved in the oil.

Acid treating of naphtha or oils.

In propane treating of lubricating oil stocks counter-current washing is necessary. Here 60 temperature may be varied from top to bottom of the tower if desired. Ethane content of the solvent may be changed.

Emulsions are avoided in this process by regulating the number and the diameters of the pipes 65 used in intimately contacting the two liquids of different gravities.

The foregoing description is merely illustrative and various changes and alternative arrangements may be made within the scope of the appended claims in which it is my intention to 70 claim all novelty inherent in the invention as broadly as the prior art permits.

I claim:

1. Apparatus for the counter-current treatment of immiscible liquids of different gravities,

which comprises a substantially vertical shell, plates dividing the shell horizontally into sections, a pipe extending from an opening in each plate a substantial distance into an adjoining section, said pipe having serrations in its free end for sub-dividing the liquid into drops, both the uppermost and lowermost sections of the shell having an inlet and an outlet. 5

2. Apparatus for the counter-current treatment of immiscible liquids of different gravities, 10 which comprises a substantially vertical shell, plates dividing the shell horizontally into sections, a pipe extending from an opening in each plate a substantial distance into the adjoining section, the pipe being provided with a plurality of openings in its side wall for sub-dividing a liquid 15 into drops, both the uppermost and lowermost sections of the shell having an inlet and an outlet.

3. Apparatus for the counter-current treatment of immiscible liquids of different gravities, 20 which comprises a substantially vertical shell, plates dividing the shell horizontally into sections, a pipe extending from an opening in each plate a substantial distance into an adjoining section, means provided on the pipes for sub- 25 dividing a liquid into drops, baffles in each section to prevent direct flow of liquids between pipes in adjoining sections, both the uppermost and lowermost sections of the shell having an inlet and an outlet. 30

4. In a process for treating a mineral oil with a solvent, the steps of continuously flowing said oil and solvent counter-currently through a contacting column, engaging the counter-currently flowing oil and solvent phases in a plurality of 35 phase contacting paths of relatively small cross-sectional area, and disengaging the oil and solvent phases to cause a layer formation thereof intermediate the ends of said column and between disconnected portions of said paths. 40

5. In a process for contacting liquid phases such as in treating a mineral oil with a solvent, the steps of continuously flowing said phases counter-currently through a contacting column, engaging the counter-currently flowing phases 45 in a plurality of phase contacting paths of relatively small cross sectional area, and disengaging the phases to cause at least one layer formation thereof intermediate the ends of said column and between disconnected portions of said paths. 50

6. In a process for treating a mineral oil with a solvent, the steps of continuously flowing said oil and solvent counter-currently through a contacting column, engaging the counter-currently flowing oil and solvent phases in a plurality of 55 phase contacting paths of relatively small cross sectional area, and disengaging the oil and solvent phases to cause layer formations thereof at a plurality of spaced points intermediate the ends of said column and between disconnected portions 60 of said paths.

7. In a process for treating a mineral oil with a solvent, the steps of continuously flowing said oil and solvent counter-currently through a contacting column, engaging the counter-currently flowing oil and solvent phases in a plurality of 65 spaced sets of contacting paths of relatively small cross sectional area, feeding the solvent and oil phases into all paths of any one set at substantially the same ratio one to the other, and disengaging the oil and solvent phases between two adjacent sets of paths to cause a layer formation 70 of said phases.

8. In combination, a column, means in said column for causing liquids to flow counter-cur- 75

rently through said column by virtue of a difference in density such as in the treatment of mineral oils, means in said column for engaging the liquid phases in a plurality of sets of phase contacting paths of relatively small cross sectional area, and means for disengaging said phases intermediate said sets, and for causing at least one disengaged phase to assume a layer formation.

9. In a process for treating a mineral oil with a solvent, the steps of flowing said oil and solvent counter-currently and serially through a plurality of spaced sets of phase contacting paths of relatively small cross sectional area, and causing layer formations at opposite ends of each set of phase contacting paths.
